UNITED STATES PATENT OFFICE.

GUSTAVE KOHNER, OF NEW YORK, N. Y., ASSIGNOR OF ONE-HALF TO EDWARD M. VOGEL, OF NEW YORK, N. Y.

DESIGN FOR A VEST.

45,047.

Specification for Design.

Patented Dec. 16, 1913.

Application filed April 14, 1910. Serial No. 555,550. Term of patent 7 years.

To all whom it may concern:

Be it known that I, GUSTAVE KOHNER, a citizen of the United States, residing at New York city, in the county of New York and State of New York, have invented a new, original, and ornamental Design for a Vest, of which the following is a specification, reference being had to the accompanying drawings, forming a part thereof.

The figure is a face view of a vest, showing my design.

I claim:

The ornamental design for a vest, as shown.

GUSTAVE KOHNER.

Witnesses:

DAVID MONTEZINOS,
KATHERINE I. SLEVIN.
